BUILDING BLOCK

Alfred Lawrence Kocher, 314 Burns Lane, Williamsburg,
Va. 23185, and Ernest A. Wiedemann, 3215 Noble
Ave., Richmond, Va. 23222

Filed Jan. 6, 1967, Ser. No. 5,336

Term of patent 14 years

(Cl. D18—2)

FIG-1

FIG-2

FIG-4

FIG-3

FIG-5

FIG-6

FIG. 1 is a view in perspective of a building block embodying our new design;

FIG. 2 is an elevation view from the back of the building block as shown in FIG. 1;

FIG. 3 is both a top and bottom plan view of the building block as shown in FIG. 1;

FIG. 4 is an elevation view from the right side of the building block showing in FIG. 1;

FIG. 5 is a view in perspective of a building block embodying our new design which is identical to that shown in FIG. 1 except the height has been decreased; and

FIG. 6 is a view in perspective of a building block embodying our new design which is identical to that shown in FIG. 1 except the height has been increased.

The characteristic features of the design reside in the portions shown in full lines.

What is claimed is:

The ornamental design for a building block, substantially as shown and described.
